UNITED STATES PATENT OFFICE.

THOMAS RODMAN, OF YOUNGSTOWN, OHIO, AND FRANK M. STEVENSON, OF SHARON, PENNSYLVANIA, ASSIGNEES TO THE PENNSYLVANIA TANK CAR COMPANY, OF SHARON, PENNSYLVANIA, A CORPORATION OF OHIO.

TANK-SUPPORT FOR TANK-CARS.

1,274,200.

Specification of Letters Patent. Patented July 30, 1918.

Application filed January 28, 1918. Serial No. 214,194.

To all whom it may concern:

Be it known that we, THOMAS RODMAN and FRANK M. STEVENSON, citizens of the United States, and residents of Youngstown, in the county of Mahoning and State of Ohio, and Sharon, Mercer county, Pennsylvania, respectively, have invented a new and useful Improvement in Tank-Supports for Tank-Cars; and we do hereby declare the following to be a full, clear, and exact description thereof.

This invention relates generally to supports and more particularly to tank supports for tank cars, and has for one of its principal objects the provision of a device of this character that may be formed of forged steel, as well as one which will be strong, durable, resilient and light.

A further object is to provide a device of this character which will be composed of few parts, will only require a minimum amount of labor to construct, and therefore reduce the cost of such article.

Generally speaking, our improved support comprises forged side members of angle shape in cross section, a tie plate, and cushion members.

While we have shown one particular form of our invention in the drawings, it will be understood that we do not wish to be limited to such construction, since various minor changes in construction and design may be made by one skilled in the art without departing from the spirit of our invention as defined in the appended claims.

In the drawings:

Figure 1 is a side elevation of our support showing its relation to a tank car;

Fig. 2 is a top plan view of one of the supports; and

Fig. 3 is a view on the line 3—3 of Fig. 2.

Referring more particularly to the drawings, the Fig. 1 designates the two side members of our improved support A, which members are substantially triangular shaped, with the forward portion 2 of said side members being concave, and the rear portion 3 being directed rearwardly to firmly support the forward part 2. The members 1 are formed of an angled cross-section, with the outer faces thereof forming the tops of the

curved tank supports 4 and the standards 4', while the other faces extend downwardly from the inside edge to form the inner sides 5 of said members. 55

The side faces 5 are cut away adjacent both of the end terminals of the members 1 to provide a projection of the top face 4 at each end, which projections are bent outwardly on a line with each other forming 60 securing lugs 6 and 7.

The members 1 are secured together and spaced apart by the plate 8 secured across the rear portions 3 thereof by rivets or bolts 9. 65

Cushion members 10 are secured across the top of the assembled support A, and held in place by bolts 11 which are counter-sunk into said cushions and pass through apertures in the top faces 4 of the members 1. 70

In Fig. 1 there is shown one of the supports A in position secured to a cross beam 12 of a car; and there also is shown a section of tank 13 resting on the cushion members 10 of the support A. 75

It will be readily seen that the improved support A shown and described herein is strong, light, resilient and durable, while it is also cheap and simple to manufacture, which will therefore provide an ideal support for steel car construction. 80

Having thus described our invention, what we claim is:

1. The combination with a car having a tank supported thereon, of a forged metal support for said tank comprising side members bent to form front and back portions which project away from each other from the point of bend at oppositely directed angles, said front portions being formed concave to correspond with the curve of said tank, said side members being angle shaped in cross section, a tie plate rigidly secured across said members, cushion members secured across the front portions of said side members, and means for securing said support to said car. 90

2. A forged metal support for tank cars comprising two side members each bent to form front and back portions which diverge outwardly from the point of bend at oppositely directed angles, said front portions be- 100

ing formed concave, said side members being angle-shaped in cross section, a tie plate permanently secured across both of said members, and cushion members secured 5 across the front portions of said side members.

In testimony whereof we, the said THOMAS

RODMAN and FRANK M. STEVENSON, have hereunto set our hands.

THOMAS RODMAN.

FRANK M. STEVENSON.

Witnesses:

CHARLES A. VANDUSLIA,

C. D. MORRISON.
